UNITED STATES PATENT OFFICE

JOHN A. FRAZIER, OF SOUTH BRAINTREE, MASSACHUSETTS

SHAPING RIDING BOOTS

Application filed March 29, 1930, Serial No. 440,090. Renewed April 12, 1932.

This invention relates to apparatus for shaping leather riding boots or the like, and has for its principal object the provision of a simple and compact machine for successively forcing the forming lasts into the leg of the boot and withdrawing the lasts from the formed boot, the successive operations being performed by a wheel or crank without injuring the leather.

Heretofore, the common method of shaping the leg of a riding boot has consisted in driving a wedge member between a pair of lasts placed within the leg and subsequently hammering the lasts off the wedge, the work being performed by hand operations at a considerable waste of time and effort and frequently resulting in damage to the wedge, the lasts and the leather of the boot. The principal objection to this old hammering process has been the frequent breakage of the driven wedge and the excessive cost of replacing the broken wedges.

It is accordingly a particular purpose of the present invention to obviate these objectionable results of the former methods by providing means for forcing the wedge into position without injury to the wedge and without excessive or troublesome effort by the operator; and also to provide means associated with the wedge and the forming lasts whereby the wedge may be inserted and withdrawn without gripping the boot itself or applying damaging impacts to the boot or the forming elements. Further objects reside in the novel features of the apparatus hereinafter described and pointed out in the appended claims.

A recommended embodiment of the invention is illustrated in the accompanying drawings, in which:

Fig. 1 is a plan view of the improved machine showing the arrangement of the parts as the wedge is forced into the boot between the lasts;

Fig. 2 is a fragmentary plan view illus-

trating the operation of pressing the boot and lasts off the wedge;

Fig. 3 is an enlarged section through the boot, taken on line 3-3 of Fig. 1;

Fig. 4 is a side elevation of the machine in 50 the position of Fig. 2;

Fig. 5 is a detail in plan of the boot and the inserted shaping members;

Fig. 6 is a plan view of the wedge;

Fig. 7 is a plan view of one of a pair of 55 bifurcated metal strips interposed between the wedge and the respective lasts;

Fig. 8 is a transverse section on line 8-8 of Fig. 7;

Fig. 9 is an elevation of the assembled 60 forming elements, the boot being omitted;

Fig. 10 is a fragmentary elevation of one side of the frame (looking outward), showing a pair of braces for holding the transverse ends of the bifurcated strips; 65

Fig. 11 is a section on line 11-11 of Fig. 10;

Figs. 12 and 13 are details of the braces; and

Fig. 14 is a sectional view illustrating a 70 cradle for the boot.

In the apparatus chosen for the purpose of illustration, the machine comprises a framework including a pair of elongate rails 21 connected in parallel relation by end cross 75 members 22 and 23 which are mounted on upright legs 24 at each corner to support the rails substantially horizontally above the floor. The rearward end member 23 constitutes a housing in which is journaled a vertical shaft 25 and through which a driven rod 26 is slidable longitudinally of the frame. The lower end of the shaft 25 carries a spur gear 27 which engages a rack 28 formed in the rod 26, and the upper end of the shaft has an 80 operating crank wheel 29. The forward end of the rod 26 is fixed to a slide 30 in the form of a crosshead mounted for longitudinal sliding movement along the rails 21. The rod and its crosshead thus constitute a plunger 85 90

operated by the wheel 29, and a central enlargement of the crosshead preferably has a recess 32 to receive the end of the wedge member of the boot shaping elements.

5 The crosshead center 31 also mounts upon its upper side a pivoted hub 33 to which is pivoted as by a pin 34 a push rod or bar 35. These pivots are arranged at right angles to each other, so that the rod 35 may be swung 10 in both horizontal and vertical planes with respect to the crosshead. This rod is employed to separate the forming elements and permit the removal of the shaped shoe, as will be explained hereinafter; hence the rod is swung to inoperative position in Fig. 1, and is in working position in Figs. 2 and 4.

Near the forward end 22 of the frame is a transverse cradle 36 for supporting the boot during insertion and removal of the shaping elements. The cradle may be formed of 20 leather or other flexible material and is preferably adjustable vertically with respect to the frame. For example, as best shown in Fig. 14, the cradle may be fastened, together 25 with depending spreading arms 37, upon collars 38 rotatable on the rails 21; and the lower ends of the arms may be connected by a cross bar 39 pivoted at 40 to one of the arms and passing through a slot in the opposite arm, the cross bar having ratchet teeth 41 locking 30 with an edge of such slot under tension of a spring 42. Hence, by twisting either or both of the collars 38 outwardly, the cradle may be tautened and elevated; and the release of the 35 ratchet will permit slackening of the cradle.

Intermediate the plunger-crosshead and the cradle, the frame is provided with supporting braces for holding the transverse ends of a pair of metal separator strips constituting part of the boot-shaping elements, the brace members being arranged removably to receive said transverse ends and to brace the same against the operation of the plunger or the lever 35. A cooperating set 40 of similar braces is provided upon each of the rails 21, so that a description of one set of members will suffice. Each set preferably comprises a pair of sleeves 43 and 44 surrounding the rail 21 in end to end relation, 45 and being rotatable on the rail but prevented from movement longitudinally of the rails as by stop collars 45 which are fixed to the rail at the outer ends of the sleeves. The respective sleeves have integral transverse 50 arms 46 and 47 at their contiguous ends, projecting radially of the sleeves and preferably longitudinally offset beyond said ends as indicated at 48 so that the two arms overlap each other approximately in the same vertical 55 plane, as best shown in Fig. 10.

Thus the sleeves may be identical in construction so that they may be used interchangeably in any of the four positions which they may occupy. To this end, the ends of the similar arms 46 and 47 have openings 49

therethrough for receiving the reduced ends 50 of U-shaped socket members 51 and 52. The ends 50 may be inserted from either end of the openings 49, and may be secured by a screw 53 (Fig. 12). Accordingly the socket members may be fixed to the respective arms 46 and 47 in such a manner that they extend in the same direction longitudinally of the frame and between the same vertical planes. The respective sockets or slots 54 and 55 open rearwardly of the frame and are normally disposed in spaced parallel relationship to receive the transverse ends of the bifurcated strips. In order that the distance between the sockets 54 and 55 of each set of braces may be self-adjusting to the lasts when the latter are wedged apart, a yielding device is preferably provided for tensioning the U-shaped members 51 and 52. Such device may comprise a rod 56 having a head on its upper end, extending through aligned apertures 57 in said members, and a spring 58 surrounding the rod and bearing upon a nut 59 at its lower end, so that the two members with their sleeve arms 46 and 47 are urged toward each other. A spacer 60 attached to one of the collars 45 as by a bolt 61 and having an inwardly bent end terminating in a tip 62 extending between the opposed faces of the members 51 and 52, is preferably provided to limit the action of the spring 58 and normally hold the members in a given position (Fig. 10).

The forming elements for shaping the contour of the leg of the riding boot shown at 63 preferably comprise a pair of wooden lasts or formers 64 and 65, occupying the front and back parts respectively of the boot leg the upper and lower parts when the boot is in the horizontal position shown in the drawings, an elongate, central wedge member 66, tapering toward its inner end and adapted to be received between the lasts, and a pair of bifurcated separators 67 and 68, each comprising two strips of flat metal fixed in parallel relation by a transverse end piece or head 69 and 70 respectively, the heads being formed of thicker metal and being receivable in the sockets 54 and 55 of the braces. A last for the foot part of the boot is also provided in the usual manner, but the foot last is not material to the present invention. The opposed flat faces of the leg lasts 64 and 65 and the wedge 66 preferably have interfitting guide tenons and grooves for centering the members as they are assembled. As shown, last 64 has a groove 71 receiving a tenon 72 of the wedge 66; the wedge has an opposite groove 73 receiving a tenon 74 of last 65; and the metal strips 67 and 68 are arranged to straddle the respective tenons between the wedge and respective lasts.

The outer end of the lasts preferably have leather facings 75 and 76 respectively; and the wedge has a protruding neck portion terminating in a metal-capped end 77 which is receivable within the recess 32 of the plung-

er crosshead. It will be observed that the protruding portion of the driven wedge is substantially shorter than the effective length of the rod 35, as indicated in Fig. 2.

5 The method of utilizing the apparatus above described for shaping the leg of a riding boot is preferably as follows: After inserting the foot last (not shown) in the foot of the boot, the leg lasts 64 and 65 are placed 10 in the leg together with the metal strips 67 and 68 and the wedge 66, the lasts and metal strips being pushed inwardly until the leg lasts abut the foot last and the strip heads 69 and 70 seat against the leather facings 75 and 15 76, with the wedge forced in sufficiently to exert a slight outward pressure on the lasts; the boot is then placed upon the cradle 36 midway between the frame rails 21 with the metal heads 69 and 70 inserted in the sockets of the 20 bracing members 51 and 52; the crank wheel is then turned to move the plunger forwardly until the capped end 77 of the wedge enters the cross head recess 32, and is then further rotated to drive the wedge between the metal 25 strips 67 and 68 and thus expand the lasts to the desired degree. It will be noted that the wedge is thus driven home without gripping the boot or making frictional contact with the other shaping elements, by a steady 30 pressure which does no damage to the wedge, and that the operation may be quickly performed with slight manual effort.

The intermediate metal strips or separators 35 67 and 68 not only constitute a support for the open end of the boot leg but also withhold the lasts from longitudinal displacement as the wedge is driven between them, and allow only the lateral component of force exerted by the wedge to be applied to the 40 lasts. During this movement of the wedge, the heads 69 and 70 of the separators and their supporting U-shaped braces are spread apart against the resistance of the yielding spring 58, the brace sleeves 43 and 44 rotating in opposite directions during such movement. After the wedge has been forced inwardly of the boot a sufficient distance to exert the proper pressure upon the leather of the boot leg, the boot and the shaping forms 45 50 may be removed from the machine and allowed to stand until the shape of the leg has set. It will be understood that, in accordance with common practice, the leather is softened by wetting or by suitable preparations, before the forms are placed therein, and that the boot is dried out and hardened before 55 the forms are removed.

In order to remove the forms, the boot is again placed in the machine in the manner 60 above described, the plunger crosshead being retracted, and the rod 35 is then swung around until its end is directed toward the projecting end of the upper last 64. By 65 rotating the wheel 29 in the same direction as before, the end of the rod is brought to

bear against the leather facing 75 above the liner head 69 (Figs. 2 and 3), and by continued rotation of the wheel the upper last and boot are forced rearwardly, thereby 70 loosening the wedge which is held in fixed position by the braced separators 67 and 68. The forms may then be withdrawn from the boot either before or after the finished boot is removed from the machine. This action, like that of crowding in the wedge, is effected 75 by a firm, steady pressure and with total absence of the pounding and hammering which is so destructive of lasts and the wedges in the prior method.

I claim:

1. Apparatus of the class described comprising a pair of lasts for shaping the leg of a boot, a wedge insertable between the lasts, separators insertable between the wedge and the respective lasts, and means for holding the separators against movement inwardly of the boot when the wedge is forced between them to spread the lasts or when the expanded lasts are forced along the separators to release the wedge.

2. Apparatus of the class described comprising a pair of lasts for shaping the leg of a boot, a wedge insertable between the lasts, separators insertable between the wedge and the respective lasts, and means for holding the separators against movement inwardly of the boot when the wedge is forced between the separators to spread the lasts or when the expanded lasts are forced along the separators to release the wedge, the separators being bifurcated and the lasts and wedge having interfitting longitudinal recesses and projections extending between the furcations for guiding the wedge and the strips in their relative movement with respect to each other and to the lasts.

3. Apparatus of the class described comprising a pair of lasts for shaping the leg of a boot, a wedge between the lasts, separators between the wedge and the respective lasts, the separators having transverse heads at their outer end portions, means for forcing the wedge inwardly of the boot to spread the lasts, means for holding said heads against movement in the direction of the wedge movement, and means for forcing one of the lasts along the separators to release the wedge after the boot has been shaped by the expanded lasts.

4. Apparatus of the class described comprising a pair of lasts for shaping the leg of a boot, a wedge between the lasts, separators between the wedge and the respective lasts, the separators having transverse heads at their outer end portions, means for forcing the wedge inwardly of the boot to spread the lasts, means for holding said heads against movement in the direction of the wedge movement, and means for forcing one of the lasts along the separators to release the wedge.

after the boot has been shaped by the expanded lasts, both said forcing means being actuated by a common propulsion means.

5. Apparatus of the class described comprising a frame having parallel rails, means for supporting the lower end of a boot between the rails, a pair of lasts in the boot for shaping the leg portion thereof, a wedge between the lasts with its outer end projecting 10 beyond the top of the boot, separators between the wedge and the respective lasts, said separators having transverse heads at their outer ends, means on the rails for supporting said heads and holding them against 15 movement longitudinally of the frame in a direction toward the foot of the boot, a cross-head movable along the rails toward the projecting end of the wedge, and means for moving the crosshead to force the wedge between 20 the separators, thereby to expand the last.

6. Apparatus of the class described comprising a frame having parallel rails, means for supporting the lower end of a boot between the rails, a pair of lasts in the boot for shaping the leg portion thereof, a wedge between the lasts with its outer end projecting beyond the top of the boot, separators between the wedge and the respective lasts, said separators having transverse heads at 25 their outer ends, means on the rails for supporting said heads and holding them against movement longitudinally of the frame in a direction toward the foot of the boot, a cross-head movable along the rails toward the projecting end of the wedge, a crank operative for moving the crosshead against the projecting end of the wedge to force the wedge between the restrained separators to expand the lasts, a rod pivoted to the crosshead midway between the rails and arranged to be 30 swung parallel to the rails with its free end abutting the outer end of one of the lasts when the crosshead is distant from the wedge, so that a subsequent movement of the crosshead in the same direction will force the rod against the said last and thereby move the last toward the inner end of the juxtaposed separator and release the wedge from 35 the expanded lasts.

7. Apparatus of the class described comprising a frame having parallel rails, means for supporting the lower end of a boot between the rails, a pair of lasts in the boot for shaping the leg portion thereof, a wedge 40 between the lasts with its outer end projecting beyond the top of the boot, separators between the wedge and the respective lasts, said separators having transverse heads at their outer ends, means on the rails for supporting said heads and holding them against movement longitudinally of the frame in a direction toward the foot of the boot, a cross-head movable along the rails toward the projecting end of the wedge, means for moving 45 the crosshead against the projecting end of the wedge to force the wedge between the retained strips, thereby to expand the lasts, a member carried by the crosshead and movable relative thereto so that its free end may 50 be brought to bear against the outer end of

one of the lasts, after the boot has been shaped by the expanded lasts, so that a subsequent movement of the crosshead in the same direction will force the said last toward the inner end of the juxtaposed separator 70 while the latter is retained by its said supporting means, thereby to release the wedge.

8. Apparatus of the class described comprising a frame having parallel rails, means for supporting the lower end of a boot between the rails, a pair of lasts in the boot for shaping the leg portion thereof, a wedge between the lasts with its outer end projecting beyond the top of the boot, separators between the wedge and the respective lasts, said separators having transverse heads at their outer ends, means on the rails for supporting said heads and holding them against movement longitudinally of the frame in a direction toward the foot of the boot, a cross-head movable along the rails toward the projecting end of the wedge, a crank operative for moving the crosshead against the projecting end of the wedge to force the wedge between the restrained separators to expand the lasts, a rod pivoted to the crosshead midway between the rails and arranged to be swung parallel to the rails with its free end abutting the outer end of one of the lasts when the crosshead is distant from the wedge, so that a subsequent movement of the crosshead in the same direction will force the rod against the said last and thereby move the last toward the inner end of the juxtaposed separator and release the wedge from 95 the expanded lasts.

9. Apparatus of the class described comprising a frame having parallel rails, means for supporting the lower end of a boot between the rails, a pair of lasts in the boot for shaping the leg portion thereof, a wedge between the lasts with its outer end projecting beyond the top of the boot, separators between the wedge and the respective lasts, said separators having transverse heads at their outer ends, means on the rails for supporting said heads and holding them against movement longitudinally of the frame in a direction toward the foot of the boot, a cross-head movable along the rails toward the projecting end of the wedge, and means for moving the crosshead to force the wedge between the separators to expand the last, the means for supporting the separator heads comprising a pair of abutting collars rotatable on each rail, the respective collars having offset jaws receiving the corresponding ends of the respective heads, said jaws being angularly movable away from each other as 110 their collars are rotated upon spreading apart of the separators by the wedge, and yielding means tending to urge the jaws toward each other.

10. Apparatus of the class described com-

prising a frame having parallel rails, means for supporting the lower end of a boot between the rails, a pair of lasts in the boot for shaping the leg portion thereof, a wedge inserted between the lasts with its outer end projecting beyond the top of the boot, flat strips inserted between the wedge and the respective lasts, said strips having transverse heads at their outer ends, means on the rails for supporting said heads and holding them against movement longitudinally of the frame in a direction toward the foot of the boot, a crosshead movable along the rails toward the projecting end of the wedge, and means for moving the crosshead to force the wedge between the strips thereby to expand the last, the means for supporting the strip heads comprising a pair of abutting collars rotatable on each rail, the respective collars having offset jaws receiving the corresponding ends of the respective heads, said jaws being angularly movable away from each other as their collars are rotated upon expansion of the strips by the wedge, and yielding means tending to urge the jaws toward each other, and a spacing member extending between the respective jaws for limiting said movement caused by said yielding means.

11. The improved method for shaping the legs of riding boots by the use of lasts or forms extending lengthwise of the boot leg and a wedge driven longitudinally between said forms, which consists in providing separators between the wedge and forms and withholding the separators from movement with the wedge so that frictional contact between the wedge and forms is prevented and the force transmitted to the lasts or forms is limited to lateral or outward pressure only.

12. The improved method as set forth in claim 11 and comprising further the loosening of the wedge from the lasts or forms after the boot leg has been shaped, which consists in effecting a relative withdrawing movement lengthwise of the boot between the wedge and the forms while the separators are withheld from movement.

13. The method as set forth in claim 11 which comprises further the application of force to the wedge in expanding the lasts or forms with a steady pressure, as distinguished from hammer blows.

14. The improved method for shaping the legs of riding boots by the use of lasts or forms extending lengthwise of the boot leg and a wedge driven longitudinally between said forms, which consists in providing separators between the wedge and forms, withholding the separators from movement, effecting a relative movement longitudinally of the boot between the wedge and forms, by pressure steadily applied as distinguished from hammer blows, first in the direction to cause lateral expansion of the forms, and subsequently in the opposite direction.

15. A boot leg shaping apparatus comprising complementary expanding elements, namely, lasts or forms insertable into the boot leg and a wedge between said forms for spreading them apart, characterized by separators between the wedge and forms, and means for restraining the separators from longitudinal movement with the wedge or the forms when either of said expanding elements is moved relatively to the others in the spreading or relaxing action.

In testimony whereof I affix my signature.
